UNITED STATES PATENT OFFICE.

HAROLD W. SHONNARD, OF EAST ORANGE, NEW JERSEY.

STERILIZER AND VALVE.

No. 824,827.

Specification of Letters Patent.

Patented July 3, 1906.

Application filed July 8, 1905. Serial No. 268,812.

To all whom it may concern:

Be it known that I, HAROLD W. SHONNARD, a citizen of the United States, residing in East Orange, county of Essex, and State of New Jersey, have invented certain new and useful Improvements in Sterilizers and Valves, of which the following is a specification.

This invention has relation to an improved valve for apparatus used in the sterilization of all kinds of articles, but more particularly for apparatus intended for the steam-sterilization of surgical dressings, &c.

The principal object of this invention is the provision of a cheap, compact, and simple form of universal valve for accomplishing the various functions hitherto carried out in an apparatus of this kind by a number of different valves.

The invention is illustrated in a preferred form in the accompanying drawings, where-

Figure 1 is a vertical median section of the sterilizing apparatus on the plane $x-x$ in Fig. 2. Fig. 2 is an end elevation of the same. Fig. 3 is a horizontal section showing the details of the door on the plane $y-y$ in Fig. 2. Fig. 4 is a perspective view of a portion of the inner rim at the front or open end of the apparatus. Fig. 5 is a detailed view of a modified form of hinge capable of use with this device, and Fig. 6 is a vertical median section of the valve in its relation to the various parts of the sterilizer.

My improved sterilizer comprises an inner chamber 1, surrounded by two concentric cylindrical chambers, one outside of the other, as shown at 2 and 3. The chamber 2 surrounds the inner chamber 1 not only on its cylindrical surface, but at the back, where the whole structure is supported by a heavy metal ring 4. A corresponding ring 5 supports the forward end of the structure and affords the necessary attachment for the various sheet-metal coverings for the concentric chambers. The whole apparatus is supported on a leg 6.

The chamber 2 may be termed the "steam-chamber" and in operation contains a body of water, as shown in the drawings, which may be heated by any desired means—as, for instance, by the live-steam coil 7. It is preferred, however, to heat the chamber 2 and its contents by means of gas-jets underneath the same, as illustrated in Fig. 1, wherein the flames issue from orifices on the upper side of the Bunsen tube 8, which is supplied with gas

from the pipe 9 and air which mixes therewith as it enters the flaring opening 10. By use of this heating means the hot gases are made to entirely surround the steam chamber 2, issuing by openings 11 at the top of the heating-chamber 3. The water to be used in the boiler or steam-chamber can be poured in through the funnel 12 when the valve 13 is open. It can be drawn off by the pipe 14 at the bottom of the chamber.

The innermost chamber 1 can be fitted up in any desired manner to receive the articles to be sterilized, and for this purpose I have shown a simple tray 15 near the bottom of the chamber 1. The closing of the sterilizer after insertion of the dressings or other articles to be treated is accomplished by means of a rotating and swinging board 16, furnished with a handle 17.

As shown in Figs. 1 and 3, a circular edge 18 of the door is intended to be firmly pressed against a proper packing 19, set into an appropriate circular groove in the end supporting-ring 5. This pressure is obtained by means of spirally-placed ribs 20 on the door, which coöperate with similarly-inclined interior ribs 21 and 22 within the ring 5.

As shown in Figs. 1, 3, and 4, the inclined rib 21 occupies a semicircle placed within the lower half of the ring 5, while the corresponding inclined rib 22 occupies the upper semicircle within the ring 5. The door itself is carried by a strong exterior lever 23, pivoted, as at 24, to the side of the ring 5. Fig. 3 shows the door open, and Fig. 1 shows it when first brought into closing position. The door having been brought into the closing position shown in Fig. 1, complete closure is effected by swinging the handle 17 from the position shown in full lines in Figs. 1 and 2 around to the position shown in dotted lines in Fig. 2. With the door in the position shown in Fig. 1 the tip 20^a of the lower spiral rib 20 on the door occupies the position shown at the opening 21^a between the two ribs 21 and 22. Of course the corresponding tip of the other spiral rib 20 occupies a corresponding position diametrically opposite. Fig. 3 shows that a gate or opening similar to the one shown at 21^a in Fig. 4 is provided on each side of the ring 5. The ribs 20, 21, and 22 all being inclined alike, it follows that when the handle 17 is revolved, as heretofore described, the ribs 20 on the door will slide against the inner inclined surfaces of the ribs 21 and 22 and will be forced

75

95

100

110

by these latter ribs to move inward or toward the right in Fig. 1. This will of course force the whole door inward, bringing the edge 18 tightly against the packing 19 and effectually sealing the chamber 1 to a manner to resist great pressures from within. In order to accommodate the rectilinear inward movement of the door 16 as a whole with its pivotal mounting, the door is carried by a stout 5 spindle 25, deeply threaded on a steep pitch and shown in Figs. 1 and 3, the pitch corresponding to the inclination of the ribs 20, 21, and 22. This spindle 25 passes through an appropriate sleeve 26, provided with means 10 coöperating with the thread in the spindle for causing relative movement between the door and said sleeve. This means preferably takes the form of a pin 27 of proper diameter screwed in through the sleeve, so that 15 its tip enters the space between two successive convolutions of the thread on the spindle 25. A knob 28 is preferably fixed to the end of the spindle 25 to facilitate drawing the door open when desired.

25 It is clear that the arrangement just described permits of rectilinear movement in and out of the door 16 without any corresponding movement of the lever 23, and so prevents any danger of jamming during operation, while also permitting an accurate close fit between the ribs 20 and 21, 22. Without means for permitting such independent movement of the door, it is obvious that a lever, such as 23, pivoted as at 24, 30 would afford an element of disturbance which would make it difficult or impossible to procure the perfect sealing of the apparatus.

In Fig. 5 I have shown a modification of the mode of mounting the lever 23, which 35 may be used instead of the form of apparatus shown in Figs. 1 and 3; but this latter is preferred, as it obviates the necessity of automatic accommodation in the movement of the lever 23. The modification shown in Fig. 5 comprises a mounting composed of a link 29, pivoted, as at 30, to the ring 5, which link is pivoted at 31 to the extremity of the lever 23. It is obvious that by use of an intermediate link 29, as shown in Fig. 5, rectilinear motion 40 of the door 16 is possible without jamming, since the lever 23 is permitted to automatically accommodate itself to the inward and outward movement of the door.

I do not claim the improved door hitherto 45 described *per se* in this application, as this has been made the subject-matter of a divisional application.

In operating the form of sterilizer shown thus far it is desirable to admit the hot steam only after a preliminary exhaustion of the innermost chamber 1, whereby the air contained in the dressings or other articles to be sterilized is removed to give place to the incoming steam. For producing this effect 50 sterilizers have been hitherto used wherein

the number of valves and pipes of greater or less complication were necessary. It is the principal object of this invention to provide a compact, single, and simply-operated valve combination for producing all the operations necessary in using the apparatus herein described. For this purpose I employ a valve-body 32, provided with a vertical stem 33, which is inserted in the top of the sterilizer, as shown in Figs. 1 and 6, passing through the chambers 3 and 2 and reaching the top of the innermost chamber 1. The body 32 is provided with a chamber 34, closed at one end by the cap 35 and at the other end by the cap 36, which forms the exterior section or member of an exhaust-valve. A safety blow-off 37 and the gage 38 are screwed into the top of the body 32 and communicate with the main chamber 34. The stem 33 extends upward into the middle of the chamber 34, 70 being provided with two opposite passages 39 and 40. The passage 39 terminates at its lower end in a small pipe 41, which lies within the chamber 2, as shown in Figs. 1 and 3, and is carried around, so as to enter the chamber 1 near the bottom thereof and under the tray 15. The upper extremity of the passage 39 terminates in the valve-seat 42. The passage opens at its lower end into the steam-space of the chamber 2, and at its upper end 75 there is provided an injector-nozzle 43, passing into the hollow cap 36 and forming therewith an exhaust-jet of well-known character. At the outer extremity of this exhaust-jet there is placed a proper valve 44, which can be opened and closed by means of the handle 45. The upper end of the opening 39 can be closed by a valve of any desired description; but I prefer the form of valve shown wherein 80 a stout rod 46 of proper diameter is shaped at its tip to supply the valve and is supplied with a thread of steep pitch, as shown at 47, passing through an appropriate boss on the cap 35. An appropriate handle 48 is fixed to the outer end of the rod 46, and by giving this handle a half-turn the valve 42 can be opened or closed at will. At the lower end of the spindle 33 the passage 39 is continued 85 into a valve-chamber 49, wherein there is placed an automatic check-valve 50, controlling the entrance 51 into the innermost chamber 1. In the position shown in Fig. 6 this valve permits passage of air upward out of the chamber 1, through the passage 51 and the perforation 52, through the right flanges 90 on the puppet-valve 50.

The operation of the double valve shown in Fig. 6 is as follows: When the dressings have been properly placed within the sterilizer and the door has been closed, the heating of the water and steam in the chamber 2 being assumed to have been accomplished, the valve-handle 48 is at first in the position shown at Fig. 2, so that communication between the passage 39 and the chamber 34 is 95

closed. In this condition the valve 44 being closed, the gage 38 will indicate the pressure of steam existing in the chamber 2. The pressure being brought to a proper point, the valve 44 is opened, and the valve-lever 48 is set diametrically opposite to the position shown in Fig. 2. The steam rushing through the jet-tube 43 and out to the open air will thus exhaust the air from the chamber 1 through the pipe 41, the opening 51, and passage 39. As soon as the gage indicates the proper degree of exhaustion the valve 44 is closed without changing the position of the handle 48. The steam will at once back up through the passage 39, closing the automatic valve 50, so that the steam will be obliged to pass through the pipe 41 to fill the chamber 1. It will be noted that during exhaustion the air is drawn out of the chamber 1 both from top and bottom. This of course supplies a double outlet and produces quicker action. When the steam is admitted, however, I prefer to cause it to enter from below, because the first steam that enters is apt to be wet, and for this reason should not come in direct contact with the objects to be sterilized. By bringing the steam up under the tray 15 any moisture produced by condensation gathers at the bottom of the chamber, and the steam which reaches the dressings is dry. When the dressings have been subjected to the hot steam for a sufficient length of time, the valve 44 is opened. The steam is immediately withdrawn by the ejector action produced by the jet 43. The continued action of said ejector will thereupon again create a vacuum within the chamber 1 and indicate same by the reverse action of the combination-gage 38. In this manner the moisture within the chamber is rapidly evaporated, and the dressings may be thoroughly dried before removal from the sterilizing-chamber. The valve-lever 48 is then turned back to the original position, as shown in Fig. 2. The valve 44 is closed and the air-cock 52 on the door 16 is then opened, which will release the vacuum within the chamber 1, whereupon the door 16 may be opened and the dressings removed.

A number of changes may be made in my improved device without departing from my

invention, and I am not to be understood as limiting myself to the details herein shown and described.

What I claim is—

1. In a sterilizer, a steam-chamber, a sterilizing-chamber, a valve-chamber, a pipe leading from said steam-chamber to said valve-chamber, an ejector-nozzle at the end of said pipe within said chamber, an exterior valve for said valve-chamber opposite said nozzle, a second pipe leading from said valve-chamber to said sterilizing-chamber and a valve controlling communication between said valve-chamber and said second pipe, substantially as described. 60

2. In a sterilizer, a steam-chamber, a sterilizing-chamber, a valve-chamber in permanent communication with said steam-chamber, a pipe leading from said valve-chamber to said sterilizing-chamber and an automatic one-way valve opening from said pipe into said sterilizing-chamber, substantially as described. 70

3. In a sterilizer, a sterilizing-chamber, a steam-chamber surrounding the same, a valve-chamber having an extension passing through the steam-chamber and abutting at the top of the sterilizing-chamber, said extension being provided with two passages opening on opposite sides into said steam-chamber and a pipe contained within said steam-chamber and leading from one of said passages to the bottom of said sterilizing-chamber, substantially as described. 75

4. In a sterilizer, a sterilizing-chamber, a steam-chamber surrounding the same, a valve-chamber having an extension passing through the steam-chamber and abutting at the top of the sterilizing-chamber, said extension being provided with two passages one of which opens into said steam-chamber and the other of which opens into the top of the sterilizing-chamber, an automatic one-way valve in said last-named opening and a pipe leading from the latter of said two passages to the bottom of the sterilizing-chamber, substantially as described. 90
